TROLLING ATTACHMENT FOR MOTOR-
BOATSAlbert J. McGrete, Oakland, Calif., assignor to
Bernhard Kilian, Alameda, Calif.

Application October 9, 1939, Serial No. 298,567

4 Claims. (Cl. 170—135)

This invention relates generally to means for slowing a motorboat to a speed suitable for trolling or other purposes and is more particularly directed to a device which may be detachably applied to the free end of a propeller shaft adjacent the propeller.

It is the principal object of the present invention to provide a device capable of being mounted on the propeller shaft adjacent the propeller to rotate therewith and functioning to reduce the driving effect produced by the propeller without materially affecting its speed of rotation, so as to retard the boat to a speed below that which would be attained by such speed of propeller rotation were said device not present, and to provide a device of this character which may be quickly and easily applied to or detached from the propeller shaft without the use of tools or other assisting devices.

One form which the invention may assume is exemplified in the following description and illustrated by way of example in the accompanying drawing, in which:

Fig. 1 is an end elevation, partly broken away, of the device of the present invention as applied to the propeller shaft upon which the propeller is mounted.

Fig. 2 is a vertical section taken on the line II—II of Fig. 1, showing the propeller in elevation.

Fig. 3 is a detail perspective view of the fitting which forms a part of the invention.

In the use of relatively small motorboats for fishing, and particularly for trolling, a relatively slow boat speed is required, whereas a boat of this character is ordinarily propelled by a relatively small high speed propeller driven by a high speed motor, either of the inboard type or of the outboard type, having a relatively high, minimum or idling speed which will produce a normal boat speed much too fast for trolling purposes and which cannot be throttled down to trolling speed without stalling the motor.

It is in such situations that the present invention will have exceptional utility in providing a means for retarding or reducing the driving effect produced by the high speed propeller without reducing the rotative speed of the propeller and motor to a degree which may stall the motor.

In the illustrated embodiment, the propeller 10 is shown mounted on the usual propeller shaft 11 and in Fig. 2 said shaft is illustrated as being of the type usually employed in connection with outboard motors and having an externally screw-threaded free end 11a.

In a standard installation the propeller 10 is retained on the propeller shaft 11 by a castellated nut. However, in the installation of the device of the present invention, the nut of the standard installation will be replaced by an elongated fitting 12 of the character illustrated in Fig. 3.

Preferably, the fitting 12 will be formed from a bar of hexagon stock and machined to provide near its outer end an annular exterior groove 13, its inner end being axially bored and internally 10 screw-threaded as at 14 and provided with transverse apertures 15 to accommodate a locking or cotter pin 16. This elongated fitting 12 will be screwed on the shaft end 11a to retain the propeller 10 in place, and a cotter pin 16 will be 15 threaded through a transverse pair of the apertures 15 and through an aligned transverse bore in said shaft end and then bent over in the usual manner to prevent accidental loosening of said fitting. Said fitting thus forms a removable 20 continuation of the propeller shaft and is rotatable therewith.

The speed retarding element comprises a relatively thin circular disc 17 which is detachably supported on the free end of the fitting 12 to the 25 rear of and closely adjacent the propeller 10, as shown in Fig. 2, and for this purpose said disc 17 is provided with an axially disposed central opening or bore 18 extending through its hub portion 19 and of a hexagonal shape comparable 30 in size and form to the cross-sectional contour of the elongated hexagonal nut or fitting 12. The disc 17 is in this manner slidably splined on the fitting 12 to rotate therewith. The hub portion 19 of said disc 17 is also provided with a 35 transverse bore 20 intersecting the axial bore 18 of the disc and formed to provide a spring abutment shoulder 21. In this transverse bore 20 is slidably disposed a latch plunger 22 having a stem 23 of reduced diameter which extends to the 40 exterior and is there provided with an actuating knob 24, a coil spring 25 surrounding the stem 23 of said latch plunger between the head thereof and the abutment shoulder 21 and normally exerting its tension to yieldingly maintain said 45 plunger engaged in the groove 13 of the fitting 12, as shown in Figs. 1 and 2.

In the use of the illustrated device, the fitting 12, which serves not only to maintain the propeller 10 on its shaft 11 but also as a means for 50 supporting and for rotating the retarding disc 17, may remain mounted on the propeller shaft and the motor may be operated to drive the boat in the usual manner.

When it is desired to operate the boat at slow 55

speed for trolling, the motor will be stopped so that the retarding or trolling disc 17 may be applied to the fitting 12. This will be accomplished by manually holding the latch plunger 22 retracted against the tension of its spring 25, while the disc 17 is slid over the free end of the fitting 12, and then releasing said plunger to engage in the groove 13 thereof. On an outboard motor this will preferably be done while the motor is swung to elevate its propeller above the water, while in an inboard motor installation it will be accomplished by reaching into the water. In either case the application or the removal of the retarding or trolling disc or plate 17 can be easily and quickly accomplished by reason of the fact that no tool or like device is needed for the purpose.

It is to be noted that the diameter of the disc 17 is somewhat less than that of the propeller blades, due to which fact the tip portions of said blades maintain, to a large degree, their normal propelling efficiency. However, it will be understood by those skilled in the art that the presence of the adjacent trolling plate 17 will effectively diminish the total propelling efficiency of the propeller, not only by spreading the propelling effort but also by acting as a drag, the retarding effect being adequate to slow the boat to a speed suitable for trolling.

From the foregoing it will be understood that the present invention involves the provision of a fitting capable of being removably secured on the free end of a propeller shaft and having a latch groove or element, and a speed retarding element or trolling disc slidably splined on said fitting by a manually actuated latch means and in a manner permitting easy and quick assembling thereon or removal therefrom without the use of tools or other assisting devices and by persons entirely unskilled in mechanics or the use of tools.

While I have shown the preferred form of my invention it is to be understood that various changes may be made in its construction by those skilled in the art without departing from the spirit of the invention as defined in the appended claims.

Having thus described my invention, what I

claim and desire to secure by Letters Patent is:

1. A trolling attachment adapted for cooperation with a mounted propeller and comprising an axial fitting adapted to be secured to the free end of the propeller shaft to form an extension 5 thereof and provided with an external latch groove, a speed retarding trolling disc axially slidable on said fitting for removal therefrom and splined thereon for rotation therewith, and a spring-pressed latch on said disc adapted to 10 engage in said latch groove to maintain said disc against accidental displacement from said fitting and manually releasable from such engagement to release said disc for removal from said fitting.

2. A trolling attachment for a propeller shaft having a screw-threaded end, said attachment comprising an axial fitting in the form of an elongated nut adapted for screw-threaded engagement on said shaft end to form an extension 20 of said propeller shaft, said fitting having formed therein an external latch engaging groove, a speed retarding trolling disc axially slidable on said fitting for removal therefrom, the axial bore of said disc having a cross-sectional contour 25 comparable to the cross-sectional shape of said fitting whereby said fitting and disc will be splined for unitary rotation, and a spring-pressed latch plunger on said disc adapted to engage in said latch groove to maintain said disc on said 30 fitting and manually releasable from such engagement to release said disc for removal from said fitting.

3. A speed retarding trolling disc having a non-circular axial bore and a transverse bore 35 intersecting said axial bore, a latch plunger slidably disposed in said transverse bore for limited movement therein, and a spring tending to project the inner end of said plunger into said axial bore, said plunger having an outer end extending from said transverse bore whereby the plunger may be manually retracted.

4. A speed retarding trolling disc having an axial bore and provided with a spring-pressed latch means normally projecting into said bore 45 and capable of manual withdrawal therefrom.

ALBERT J. MCGRETE.
